UNITED STATES PATENT OFFICE

CHARLES A. MOORE, OF EDINA, MINNESOTA

HEATING, HUMIDIFYING, AND VENTILATING APPARATUS

Application filed August 15, 1924, Serial No. 732,348. Renewed April 1, 1929.

My invention relates to improvements in apparatus for heating, humidifying and ventilating chambers, particularly though not exclusively, for the storage of perishable commodities.

Devices of the instant class, wherein electricity is employed as the heating medium, have come into demand. The necessity of conservation in the use of electricity for such purposes, due to the cost thereof, renders it desirable that the apparatus employed be highly efficient.

An object of my invention is to supply an improved apparatus of the present kind designed to provide for the heating, humidification and ventilation of a chamber, said apparatus being simple, durable, relatively inexpensive in construction and capable of ready installation, the structural arrangement of parts making for economy in the use of the heating medium employed.

With the foregoing and other objects in view, which will appear in the following description, the invention resides in the novel combination and arrangement of parts and in the details of construction hereinafter described and claimed.

In the drawings, Fig. 1 is a vertical, central, sectional view of an apparatus embodying my invention, the same being shown as installed within a structure forming a chamber as for the storage of perishable goods and Fig. 2 is a plan view of the apparatus.

Referring to the drawings, it will be seen that the apparatus includes three concentric conduits. The inner conduit consists of an upright pipe 10 opening at its lower end near the floor 11 of the chamber A, the upper portion of said pipe being projected through the ceiling 12 of the chamber into the outer atmosphere. The intermediate conduit comprises a pipe 13 encircling the pipe 10 throughout the greater part of its length, the upper end of said pipe 13 opening into the chamber A near the ceiling thereof. The lower end of the pipe 13 has branches 13^a, 13^b leading horizontally therefrom, the branch 13^a being projected into the outer air through the wall 14 of the chamber A near the floor 11, the other branch 13^b opening into the

chamber A at the lower portion thereof. The outer conduit is an upright drum-like structure encircling the inner and intermediate conduits and communicating at its upper end with the chamber A near the ceiling 12 and at its lower end with said chamber at the floor thereof. Said outer conduit comprises a tubular tank c and a cylindrical base 15 of sheet metal. Said base 15 rests on a ring-like footing 16 placed over a drain 17 in the floor 11 of the chamber A and has a number of apertures 15^a formed in the lower margin thereof. The tank c, consisting of an inner wall 18, outer wall 19 and bottom 20, is supplied with water through a valved feed pipe 21, an overflow pipe 22, emptying into the drain 17, being provided to limit the high water level within said tank.

Water within the tank c is vaporized to humidify the air in the chamber and the air within each of the three conduits is heated by means of a heating device disposed between the outer and intermediate conduits. The heating device illustrated comprises a number of spaced electric heating elements 23 of conventional form, the same being secured at their ends to upper and lower spacer rings 24, the former being fitted with hooks 25 caught over the upper edge of the inner wall 18 of the tank c.

Disposed between the intermediate and outer conduits, the elements 23 heat the three ducts and the air therein contained. To best obtain vaporization of the water in the tank c under operation of heater elements of minimum capacity, I closely encircle the inner wall 18 of the tank c with a sleeve 26, to the lower margin of which are applied spacer feet 27 for holding said sleeve with the lower edge thereof short of the bottom of the tank c. The sleeve 26 is of a height bringing the upper edge thereof short of the high water level in the tank. Said sleeve 26 confines a limited quantity of water in the restricted space between it and the wall 18, the temperature of said water in said space being readily raised to the vaporizing point. The larger volume of water, outside of the sleeve 26, being able to circulate under the sleeve and over the same, is tempered by such circula-

tion and thereby economically prepared for vaporization.

The branch 13^a of the intermediate conduit 13 furnishes ingress for air from without the chamber A to the interior thereof and is fitted with a damper 28. The inner conduit provides for the egress of vitiated air from the chamber, said conduit or pipe 10 being fitted with a damper 29. With the dampers 28, 29 open, the movement of air through the apparatus is as follows: Fresh air enters the branch 13^a from without the chamber A and rises through the hot intermediate conduit 13 into the upper portion of the chamber. Settling along the relatively cold walls to the floor of the chamber, the air enters the apertures 15^a in the base 15, a part thereof rising through the hot outer conduit and again passing into the upper portion of the chamber, and the remainder passing upward and out of the chamber through the warm inner conduit 10. The proximity of the lower end of the conduit 10 to the floor of the chamber provides for the egress from the chamber of the coldest vitiated air, the purer, warmer air entering the base 15 being started, through the outer conduit, on another cycle of the chamber, as indicated above. The movement of air traced in the foregoing description is brought about, as will be readily understood, due to the heating of the three conduits by the heating elements 23. In this connection, it will be noted, that the incoming air is tempered in the intermediate conduit or pipe 13, before it comes into direct contact with the heating elements 23. This arrangement permits of maintaining the temperature of the heating elements at a high degree, whereby vaporization of the water in the tank c can be effected with heating elements of minimum capacity. It will be further noted that no waste of heat is occasioned in raising the temperature of the air within the inner conduit or pipe 10 to cause the egress of air from the chamber A through said pipe. Only enough heat reaches the interior of said pipe 10 to cause the desired exhaustion of air from the chamber, the balance of the heat from the elements 23 being used to the best advantage in the manner hereinbefore described.

Changes in the specific form of my invention, as herein disclosed may be made within the scope of what is claimed without departing from the spirit of my invention.

Having described my invention, what I claim as new and desire to protect by Letters Patent is:

1. The combination with a structure forming a chamber, of a draft conduit providing communication between the outer atmosphere at the upper portion of the structure and the lower portion of the chamber, a second draft conduit enclosing said first conduit and providing communication between the outer atmosphere at the lower portion of the struc-

ture and the upper portion of the chamber, a third conduit embodying a tubular tank having inner and outer walls, said third conduit enclosing said second conduit and providing communication between the upper and lower portions of said chamber, a baffle wall within said tank disposed in near proximity to the inner wall of the tank, the lower edge of said baffle wall falling short of the bottom of the tank and the upper edge of said wall falling short of the top of the tank, and a heating element arranged in the space between the inside of said inner wall of said tank and the outside of said second conduit. 70 75

2. The combination with a structure forming a chamber, of three concentrically arranged draft conduits, the inner conduit providing communication between the outer atmosphere at the upper portion of the structure and the lower portion of the chamber, the intermediate conduit providing communication between the outer atmosphere at the lower portion of the structure and the upper portion of the chamber, the outer conduit providing communication between the upper and lower portions of said chamber, a container for water and a heating element associated with said outer conduit and container, said element serving primarily, to vaporize water in said container and to heat air in said outer conduit and, secondarily, to heat the air in said intermediate and inner conduits. 80 85 90 95

3. The combination with a structure forming a chamber, of a draft conduit providing communication between the outer atmosphere at the upper portion of the structure and the lower portion of the chamber, a second draft conduit enclosing said first conduit and providing communication between the outer atmosphere at the lower portion of the structure and the upper portion of the chamber, a third conduit enclosing said second conduit and providing communication between the upper and lower portions of said chamber, a tank embodied in said third conduit and a heating element associated with said tank, said element being adapted to heat and vaporize water in said tank and to heat air in all of said conduits. 100 105 110 115

4. The combination with a structure forming a chamber, of a draft conduit providing communication between the outer atmosphere at the upper portion of the structure and the lower portion of the chamber, a second draft conduit enclosing said first conduit and providing communication between the outer atmosphere at the lower portion of the structure and the upper portion of the chamber, a third conduit enclosing said second conduit and providing communication between the upper and lower portions of said chamber, and a heating element arranged in the space between the inside of said third conduit and the outside of said second conduit. 120 125 130

5. The combination with a structure forming a chamber, of three draft conduits, the first providing communication between the outer atmosphere at the upper portion of the structure and the lower portion of the chamber, the second draft conduit providing communication between the outer atmosphere at the lower portion of the structure and the upper portion of the chamber, the third conduit providing communication between the upper and lower portion of said chamber, and a heating element for heating the air in all of said conduits, said element being arranged to impart less heat to the air in the first conduit than to the air in either of the other conduits. 70
6. The combination with a structure forming a chamber, of three draft conduits, the first providing communication between the outer atmosphere at the upper portion of the structure and the lower portion of the chamber, the second draft conduit providing communication between the outer atmosphere at the lower portion of the structure and the upper portion of the chamber, the third conduit providing communication between the upper and lower portion of said chamber, a water container, and an element for heating water in said container and air within said conduits, said element being arranged to impart heat to the water in said tank and to the air in said third conduit in greatest proportion and to the air in said second and third conduits in lesser proportion. 80
7. The combination with a structure forming a chamber of three draft conduits within said chamber, one conduit for the ingress of air to the chamber, another conduit for the egress of air from the chamber, a third conduit providing communication between one portion of the chamber at one elevation, and another portion thereof at another elevation, and means for affecting the temperature of the air in all of said conduits, the air in the egress conduit in least degree. 85
8. The combination with a structure forming a chamber, of three upright draft conduits, one communicating at its upper end with the outer air and at its lower end with the lower portion of the chamber, another conduit communicating at its upper end with the upper portion of the chamber and at its lower end with the outer air, and the third a conduit opening at its upper end into the upper portion of the chamber and at its lower end into the lower portion of said chamber, and means for affecting the temperature of the air in all of said conduits to set up a natural flow of air therein. 90
9. The combination with a structure forming a chamber, of three upright draft conduits, one conduit opening at its upper end into the upper portion of the chamber and at its lower end into the lower portion thereof, a second conduit communicating at its lower end with the lower portion of the chamber and at its upper end with the outer air at a higher elevation, and a third conduit communicating at its upper end with the upper portion of the chamber and at its lower end with the outer air at a lower elevation, said conduits being concentrically arranged, the first conduit serving to set up an internal circulation of air within the chamber, by gravity, and the second and third conduits providing for the ingress and egress of air into and out of the chamber, by gravity. 95
10. The combination with a structure forming a chamber, of three upright draft conduits, one conduit opening at its upper end into the upper portion of the chamber and at its lower end into the lower portion thereof, a second conduit communicating at its lower end with the lower portion of the chamber and at its upper end with the outer air at a higher elevation, and a third conduit communicating at its upper end with the upper portion of the chamber and at its lower end with the outer air at a lower elevation, said conduits being arranged in near proximity to each other, the first conduit serving to set up an internal circulation of air within the chamber, by gravity, and the second and third conduits providing for the ingress and egress of air into and out of the chamber, by gravity. 100
11. The combination with a structure forming a chamber, of three upright draft conduits, one conduit opening at its upper end into the upper portion of the chamber and at its lower end into the lower portion thereof, a second conduit communicating at its lower end with the lower portion of the chamber and at its upper end with the outer air at a higher elevation, and a third conduit communicating at its upper end with the upper portion of the chamber and at its lower end with the outer air at a lower elevation, the first conduit being arranged in near proximity to one of the other conduits, the first conduit serving to set up an internal circulation of air within the chamber, by gravity, and the second and third conduits providing for the ingress and egress of air into and out of the chamber, by gravity. 105
